(57) **CLAIM**

The ornamental design for a display screen with graphical user interface, as shown and described.

DESCRIPTION

FIG. 1 is a front view of a first embodiment of a display screen with graphical user interface showing the new design; and, FIG. 2 is a front view of a second embodiment of the display screen with graphical user interface.

The broken lines shown in the drawings represent portions of the display screen with graphical user interface that form no part of the claimed design.

1 Claim, 2 Drawing Sheets

FIG. 1

FIG. 2
